UNITED STATES PATENT OFFICE.

DEWITT C. CARY, OF BALTIMORE, MARYLAND.

IMPROVEMENT IN RUFFLING ATTACHMENTS FOR SEWING-MACHINES.

Specification forming part of Letters Patent No. 58,376, dated October 2, 1866.

To all whom it may concern:

Be it known that I, DEWITT C. CARY, of Baltimore, in the county of Baltimore, in the State of Maryland, have invented a new and useful Improvement in Sewing-Machine Attachments for Ruffling or Gathering Fabrics; and I do hereby declare that the following is a full, clear, and exact description of the construction and operation of the same, reference being had to the accompanying drawings, making a part of this specification, in which—

Figure 1 is a front view of a sewing-machine with the attachment in position; Fig. 2, a side view of the attachment; and Fig. 3 shows the kind of bar used to attach the invention to another class of machines.

Similar letters of reference indicate corresponding parts in the several figures.

The attachment consists of the spiral spring R, working in the tube A, which is a segment of a circle, through which spring passes the ruffling-bar B B, having at its lower end a thin plate of steel, (marked L₁) curved so as to move easily over the plate of the machine. At the upper end of the bar B B is a nut, N, to prevent the bar from flying out of the tube when the spring relaxes. Through the lower part of the ruffling-bar B B passes the pin p, working through slots in the tube A, and holding the spiral spring R. The outer end of the pin p has a small hook to attach it to the strap T. Motion is communicated to the attachment from the needle-arm of the machine by means of the strap T, the lower end of which is hooked on to the pin p and the upper end connected to the bar b and cap P by clamp-screw C and slotted bar S.

As the needle-arm rises the bar B B is drawn up ready to make the plait or ruffling; as the arm descends the steel plate or ruffler L, operating upon the fabric, shoves it to its place under the spring g, where it is held until, being operated upon by the regular feed of the machine, it is carried under the needle and stitched, from whence it passes out gathered

or ruffled, the spring-detent g holding the work from being drawn back by the return of the ruffler L.

By means of the slotted bar S and clamp-screw C the gathering or ruffling may be made fine or coarse, as desired.

Owing to the different manner of constructing sewing-machines, I make no particular claim as to the manner of fastening the attachment to the machines. In the accompanying drawings it is shown to be fastened to the head of the machine by means of the bar D. This is the manner of attaching to all machines of the Howe and Willcox & Gibbs class. To the Wheeler & Wilson and Grover & Baker class it may be attached by means of a bar similar to D to the plate of machine, altering the shape of the bar, as shown in Fig. 3, in which d is the bar and A the segmental tube or guide.

What I claim as my invention, and desire to secure by Letters Patent, is—

1. The curved or segmental guide A, in the described combination, with the bar B carrying a ruffling-plate, L.
2. The spring R, when employed in connection with the ruffling-plate L and bar B, substantially as and for the purposes set forth.
3. The connecting-strap T, connected to the head of the needle-bar or other suitable needle-operating mechanism, to actuate the ruffling device, substantially as described.
4. In combination with the aforesaid ruffling mechanism A B L, the slotted bar S and clamp-screw C, for varying the fineness of the ruffling.
5. The spring-detent g, constructed and employed as described, to hold the work from being drawn back by the return motion of the ruffler.

DEWITT C. CARY.
